DEVICE FOR FLUES, CHIMNEYS, AND THE
LIKE

Johannes Haag, Neunkirchen, Germany

Application March 12, 1938, Serial No. 195,654
In Germany July 2, 1937

8 Claims. (Cl. 266—15)

The present invention relates to a device for use in connection with the outlet openings of chimneys, flues and the like connected to converters, cupolas, or the like.

5 The object of the invention is to provide a device which makes it possible not only to protect the surroundings of the furnace against discharge, for instance of glowing clinker particles, but practically entirely to recover the solid, frequently valuable waste matter.

10 The invention consists substantially in this, that a roof or covering extending beyond the walls of the chimney, the flue or the like is provided, the distance of which from the place of emission is made such that incrustations can just form from the waste particles which are carried along. For this purpose the roof or covering may be made adjustable. According to one suitable constructional form there are suspended at the 15 edges of the covering or roof freely swinging iron chains, bars or other sections in the form of a curtain or in the form of a plurality of curtains which serve for preventing the sparks and emitted particles which are carried along from flying further. The lower side of the covering or roof is 20 preferably covered with sheet metal, so as to provide a smooth surface from which the adhering incrustations can be easily removed. The roof or covering is particularly effective, when it projects beyond the wall of the chimney or the like by about $\frac{3}{4}$ to $1\frac{1}{2}$ meters.

25 Further details of the invention will be gathered from the following description.

The invention besides being very simple has the 30 advantage that for instance persons working in the vicinity of a blowing converter are completely protected from injury, for instance through glowing pieces or through sparks, even when a very strong wind is blowing or the draught of the 35 waste gases is very great. Moreover, it has been found that the immediate vicinity and the more distant surrounding of the furnace are well protected from the nuisance of dust. More particularly, however, the arrangement according to the 40 invention enables the emitted particles to be recovered and used again, which would otherwise be wasted and would even be a source of nuisance to the surroundings, such for instance as particles of lime, iron, slag or the like.

45 In the accompanying drawing some constructional forms of the device according to the invention are illustrated by way of example.

In the drawing:

50 Fig. 1 diagrammatically and partially in section shows parts of a converter plane in which the

device according to the invention is mounted over the converter chimney,

Fig. 2 illustrates a sectional detail view of the device according to the invention on a larger scale,

5 Figs. 3 and 4 show further modifications of the device according to the invention on a larger scale.

According to the present invention a covering 10 is provided above the outlet opening 11 of the 10 chimney 7. This covering 10 may, for instance, consist of reinforced concrete, but may, of course, also be made of some other refractory material. The covering 10 is adjustably connected to the top of the chimney. In the example shown, the covering 10 is supported by six broad-flanged supporting members 12 which extend through the covering 10 and are screwed or welded to girders 13 arranged on top of the covering 10. All the 15 supporting members 12 are of the same length. The lower end of the supporting members 12 is provided with a longitudinal slot 14. A screw 15 passed through the upper edge of the chimney extends through the slot 14 of each supporting member 12 and winged nuts 16 on the screws 15 20 serve to fix the covering 10 in the adjusted position in which it may be arranged in parallel or under an angle to the upper edge of the chimney. Covering 10 is adjusted to such a distance from the emission source of the discharged heated particles, gases and the like that incrustations will 25 readily form from these discharges and adhere to the exposed surfaces of plate 18 and the curtain elements to be described below. 17 are reinforcing members of the covering 10, and 18 is a 30 seamless lining fixed to the lower surface of the covering 10 and consisting for instance of sheet iron of a thickness of about 18 mm. The lining 18 may, of course, be welded together from separate sheets.

35 All around the edges of the covering 10 one or more movable curtains 19 are provided which, as shown in detail in Figs. 2-4, may be of various constructions. For instance, as illustrated in Fig. 2, channel irons 20 are fixed to the lower surface of the sheet iron lining 18 to the flanges of which flat bar members 21, having for example the dimensions $30 \times 5 \times 2000$ mm., are connected by means of S-shaped hooks or loops 22. In this 40 manner a double curtain is obtained along the edge of the covering 10. This arrangement allows great mobility of the curtains, so that the individual members of the curtains may, by wind blowing past them or even by the draft of the 45 converter gases, be moved and caused to strike 50 the lining 18. The curtains 19 are provided with 55

against one another, whereby the formation of incrustations is prevented altogether or incrustations or the like formed already are thrown off.

Instead of using flat bars 21, as shown in Fig. 2, 5 two rows of angle irons 23 or chains 24 or in combination one row of angle irons 23 and one row of chains 24 may be connected to the lower side of the covering 10 in the manner described and as shown in Fig. 3.

10 As indicated in Fig. 4 a profile iron 25 of any desired kind may, simply by means of a hook formed at its end, be connected to an angle iron 26 fixed to the lower side of the sheet iron 18. In this manner a curtain consisting of a single row 15 of elements only is obtained. Of course, connecting angle irons 26 and single rows of suspended flat bar members 21, angle irons 23 or chains 24 may be used, as well as channel irons one or both flanges of which carry profile irons 20 25 of any kind.

The waste gases and lighter glowing iron particles flowing from the converter or the like are deflected by the roof, the coarser particles rebounding.

25 The particles which are not caught by the covering 10 are caught by the curtain or curtains consisting of flat bar elements, angle irons, chains, profile irons of any kind or the like, where they adhere to form incrustations or fall 30 down. After the curtain elements have become encrusted to a sufficient degree to warrant cleaning the same, the incrustations are removed from plate 18 and the curtain elements by scraping or some similar procedure. The cleaned curtain 35 and plate elements are then remounted in proper place and the material removed therefrom is treated to recover the valuable elements thereof.

What I claim is:

1. A device for use in connection with the outlet opening of chimneys, flues and the like connected to converters, cupolas or the like, comprising 40 a covering, having a reinforced concrete base and a seamless lining of sheet metal connected to the lower surface of said covering, supporting 45 members rigidly connected to said covering and adjustably arranged with regard to said outlet opening of said chimney by a slot and screw connection with said chimney walls, flanged irons connected to the edges of said seamless lining, 50 S-shaped hooks suspended from said flanged irons, and a bar iron swingably connected to each of said S-shaped hooks, said bar irons forming a movable curtain all around the edge of said covering and said outlet opening.

55 2. A device for use in connection with the outlet opening of chimneys, flues and the like connected to converters, cupolas or the like, comprising a covering, having a reinforced concrete base and a seamless lining of sheet metal connected to the lower surface of said covering, supporting 60 members rigidly connected to said covering and adjustably arranged with regard to said outlet opening of said chimney by a slot and screw connection with said chimney walls, flanged irons 65 connected to the edges of said seamless lining, S-shaped hooks suspended from said flanged irons, and a chain swingably connected to each of said S-shaped hooks, said chains forming a movable curtain all around the edge of said covering and said outlet opening.

3. An attachment for the tops of chimneys receiving the waste gases and the particles carried along with them from the furnaces of converters, cupolas, and the like comprising in combination, a substantially horizontal plate arranged above and across the chimney top appropriately remote therefrom, and a plurality of parallel longitudinal members suspended side by side from the rim of said plate. 5

4. An attachment for the tops of chimneys receiving the waste gases and the particles carried along with them from the furnaces of converters, cupolas and the like comprising in combination, a substantially horizontal plate arranged above and across the chimney top appropriately remote therefrom, and a plurality of parallel longitudinal particle intercepting and collecting members detachably suspended side by side with small gaps between them from the rim of said plate. 10

5. An attachment for the tops of chimneys receiving the waste gases and the particles carried along with them from the furnaces of converters, cupolas, and the like comprising, in combination, a substantially horizontal plate detachably arranged above and across the chimney top, 15 moderately remote therefrom and having a larger diameter than said top, and a plurality of parallel longitudinal members suspended side by side from the rim of said plate and terminating adjacent the plane of said top. 20

6. An attachment for the tops of chimneys receiving the waste gases and the particles carried along with them from the furnaces of converters, cupolas, and the like comprising in combination, a substantially horizontal plate of 25 reinforced refractory material arranged above and across the chimney top moderately remote therefrom; ledges affixed to the bottom of said plate, and a plurality of parallel longitudinal particle intercepting members suspended side by side from said ledges. 30

7. An attachment for the tops of chimneys receiving the waste gases and the particles carried along with them from the furnaces of converters, cupolas, and the like comprising in combination, a substantially horizontal plate of reinforced refractory material arranged above and across the chimney top at an appropriate distance therefrom; ledges affixed to the bottom of said plate, and a plurality of longitudinal particle intercepting and collecting members suspended from said ledges side by side with narrow gaps between them and terminating adjacent the plane of the said top. 45

8. An exteriorly accessible attachment for the tops of chimneys receiving the waste gases and the particles carried along with them from the furnaces of converters, cupolas, and the like; comprising in combination, a substantially horizontal flat plate arranged above and across the chimney top at some distance thereover and adapted to be adjusted in height and to be detached from, and re-attached to, the chimney top; and a plurality of parallel longitudinal members suspended side by side from the rim of said plate on all sides thereof and adapted to be detached from, and re-attached to, said rim, substantially as shown and described. 55
